UNITED STATES PATENT OFFICE.

EDWIN FRANCIS CREAGER, OF LANCASTER, PENNSYLVANIA.

DESIGN FOR A BALL RETAINER AND SEPARATOR.

SPECIFICATION forming part of Design No. 30,182, dated February 14, 1899.

Application filed January 23, 1899. Serial No. 703,187. Term of patent 14 years.

To all whom it may concern:

Be it known that I, EDWIN FRANCIS CREAGER, a citizen of the United States, residing at Lancaster, in the county of Lancaster and

5 State of Pennsylvania, have invented and produced a new and original Design in Ball Retainers and Separators; and I do hereby declare the following to be a full, clear, and exact description of the invention, such as 10 will enable others skilled in the art to which it appertains to make and use the same.

The design herein illustrated is for a retainer or separator to hold and separate a number of balls—such, for example, as are 15 commonly employed in bicycle-bearings.

15 The distinguishing feature of the design is the form, which approximates a semicylinder, the upper surface being in the form illustrated, finished with a slight inward curve 20 vanishing in a central or axial space. Centering in the angle formed by the junction of

the surfaces are a series of perforations, which if extended in a plane would be substantially elliptical in outline or circumference.

In the drawings, Figure 1 is a top plan view 25 of the retainer and separator; Fig. 2, a bottom plan view, and Fig. 3 a transverse section.

1 indicates the inclosing surfaces, which when in place will surround the cone; 2, the top surface with relation to the positions of 30 the drawings; 3, the axial space, and 4 the perforations.

What I claim is—

The design for a ball retainer and separator substantially as shown and described. 35

In testimony whereof I affix my signature in presence of two witnesses.

EDWIN FRANCIS CREAGER.
